UNITED STATES PATENT OFFICE.

WILLIAM L. HORNE, OF CHICAGO, ILLINOIS.

IMPROVEMENT IN STEAM-PUMPS.

Specification forming part of Letters Patent No. 129,891, dated July 30, 1872.

SPECIFICATION.

I, WILLIAM L. HORNE, of Chicago, Illinois, have invented certain new and useful Improvements in Pumps, of which the following is a full, clear, and exact description, reference being had to the accompanying drawing making part of this specification, and consisting of two sheets, in which—

Figure 1 is a vertical section; Fig. 2, an enlarged detail; Fig. 3, a detail; Fig. 4, a side elevation, showing the siphon.

My invention is an improvement on pumps already patented to me; it relates to that class of pumps in which the water is first raised by atmospheric pressure. The objects of my invention are, chiefly, to produce a continuous instead of an intermittent flow of water, and to so construct the siphon through which the water is discharged that air will not accumulate in its highest point.

In the drawing, A B represent two cylinders; C D, floating plungers, one in each cylinder; a a', openings through each plunger; b b', valves to close the openings a a'. The space between the plungers and cylinders will be filled with water, which will serve as packing. The chamber or cylinder A communicates with the passage E, and the cylinder B communicates with the passage F. E and F are separated by the partition G, and both communicate with the outlet J through the valve-chamber K. h h' are valves. H is the inlet-pipe; c, a valve, which closes the passage-way from H to the cylinder A; and c', a valve to close the passage from H to the cylinder B. d d' are bars to arrest the upward movement of the valves c c'. In this pump I use steam to create a vacuum, and also, when desired, to force the water from the cylinders, the water being forced from and a vacuum being created in the two cylinders alternately, as follows: e e' are pipes, through which steam is admitted into the cylinders A B through the passages f f', and above the plungers C D. I is a walking-beam, supported upon a shaft having bearings in the sides or walls of the passages E F, one end of which shaft extends outside of the wall, and has a bar or lever attached thereto for the purpose of starting the pump, after which the operation will be automatic. g g' are rods or bars placed

within the steam-passages f f', of such length that when in the position shown in Fig. 1 one will extend a short distance into one cylinder, and the other side will be on a line with the top of the cylinders. The ends of the beam I are inserted into the rods or bars g g'. This beam also passes through the valves i i', which valves open and close the openings u u and u' u' from the steam-passages g g' to the passages E F. r r' are valves attached to the bars g g', for the purpose of opening and closing the steam-inlets. The rods or bars g g', the valves i i', and the valves r r' are all operated by the beam I. Any air which may be in the cylinders A B when the plungers rise will be forced out through the openings u u u' u' into the water-passages and carried out with the water, and, by means of these openings, the condensation of the steam may be more rapid. The beam I is located wholly within the walls of the pump. To prevent the escape of steam from the passages f f', and also to prevent the passage of water around the beam into f f', I use a piece of rubber, k, fitted upon I, and back of this piece of rubber (see Fig. 2) is a rocking cup, v, of metal, fitted tightly against the rubber and pivoted at t upon the beam I, so that the pressure of the rubber upon the valve i will be uniform though the position of the beam changes. When the water is not to be raised to a greater height than it can be forced by the pressure of the atmosphere, I use a siphon, S, for a discharge-pipe. As in one of my former patents with this improvement, it is flattened at the top, (see Fig. 4, L;) and by this means I accomplish an important result.

When the siphon has the usual form, curved at the top, it is impossible to make the pump work, for the reason, as I now believe, that air accumulates at the top of the siphon and is carried back into the cylinders, destroying the vacuum, and though the tendency of the water flowing through the siphon is to carry out this air, yet it moves in large bubbles, which rise up through the flowing water back to the top of the siphon and thence into the cylinders; but, when the flattened siphon is used, the air is broken up into small bubbles, so that its tendency to rise is counteracted by the outflowing current of water, and it cannot accumulate in the siphon. Whether this theory

is entirely correct I cannot say; but I know, from repeated trials, that the pump will not work with the siphon made in the usual form, while it will work constantly and perfectly when the siphon is flattened at the top, as described and shown.

Operation.

Suppose the pump to be in operation, as shown in Fig. 1, C is at the top of A and D at the bottom of B. C, ascending, comes in contact with the lower end of g, forcing it up, carrying up that end of I, opening the steam-inlet from e, and closing the openings u u'; at the same time the other end of the beam I was carried down, closing the steam-inlet from e', and opening u' u''. The parts being in this position, steam will pass from any suitable boiler through e and f to the top of the plunger C, which, by the pressure of the steam, will be forced down, forcing the water in the lower part of cylinder A out through E K J, the valve h being opened and the valve e being closed; at the same time the valve b' will open and the steam in the upper part of B will condense, forming a vacuum. Water will be forced by the pressure of the atmosphere through pipe H, opening the valve c' into the cylinder B, and D will be forced up to the top of B, and, coming in contact with g', will elevate the depressed end of the beam I, opening e', closing u' u'', closing e, and opening u u'; at the same time the valve b will open and the steam in the upper part of A will condense; water will be forced into A through the pipe H and valve e, and steam passing through e' g' will force down D, forcing out the water on that side through F K J; the valve h' being then open and h closed. This operation being constantly, repeated a continuous stream will be discharged.

With this pump water can be raised by atmospheric pressure from twenty-five to twenty-eight feet, and may then be discharged at a steam-pressure equal to the first atmosphere; or it can then be forced to any reasonable height by the use of steam at the required

pressure. I have thus combined my former pump with a force-pump, and also have a continuous flow of water. I only use the siphon when the water is to be raised not over twenty-eight feet; when to be raised higher than that I use an ordinary discharge-pipe. By extending the long leg of the siphon the water will be discharged at a pressure less than that of the first atmosphere.

Instead of pivoting the rocking cup to the beam it may be held against the rubber by a spring and still have the rocking movement.

When this pump is working the attendant will know that the cylinders are filled at each stroke, and that the pump is doing its full work, because the plungers will not operate the rods g g' unless the cylinders are filled.

What I claim as new is as follows:

1. The combination of the cylinders A B, plungers C D, each provided with a central passage and valve, inlet passage or chamber H, provided with the valves c c' with the discharge-passages E F, and suitable devices for admitting steam to the cylinders, so that the water may be discharged above the pump and the operation performed partly by force and partly by suction, substantially as specified.

2. The walking-beam I, in combination with the discharge-passages E F and steam-chambers, when constructed and arranged to operate within the same, so as to dispense with any additional frame-work for its support, substantially as described.

3. The beam I, rods g g', valves i i' and r r', in combination with the cylinders A B, plungers C D, inlet-pipe and valves H c c', and outlet-passages E F, substantially as and for the purposes specified.

4. The rubber spring k and rocking cup v, in combination with the valve i, substantially as and for the purposes specified.

5. The siphon S when flattened at the top, substantially as and for the purpose specified.

WM. L. HORNE.
